UNITED STATES PATENT OFFICE.

CHARLES H. SPINK AND VICTOR D. GARNS, OF DAVENPORT, IOWA.

AUTOMATIC RESTAURANT.

1,388,975.

Specification of Letters Patent. Patented Aug. 30, 1921.

Application filed July 26, 1920. Serial No. 398,900.

To all whom it may concern:

Be it known that we, CHARLES H. SPINK and VICTOR D. GARNS, citizens of the United States, residing at Davenport, in the county 5 of Scott and State of Iowa, have invented certain new and useful Improvements in Automatic Restaurants, of which the following is a specification.

This invention relates to an automatic apparatus for serving meals in a restaurant or other like establishment and has for its principal object the production of a system that may be used in restaurants with great efficiency, sanitation, reduced cost of operation 15 and allow comparatively cheap meals to be served.

Another object of the invention is to provide a lunch room or other eating establishment and by means of which a customer entering the lunch room may make his selection from the bill of fare, order his meal and have it mechanically served, thus dispensing with the employment of waiters and consequently reducing the cost of maintaining 20 and operating such an establishment.

Another object of the invention is the production of a system of this nature that may be used efficiently, eliminating entirely the necessity of giving orders to, and receiving 30 food from waiters as is the common practice thus insuring sanitation and will be quick and sure, and will tend to do away with the noise and confusion usually attendant in such dining establishments.

Another object is to provide a device of 35 this nature which economizes space for serving the food and dishes, which reduces the number of employees, which saves time in the service of patrons, which enables the food to be served to the patron at his designated table by a semi-automatic mechanism which attracts his attention and is likely to draw trade.

Another object of the invention is to produce 45 a system whereby the customer will be individually served and after having eaten he will place his dishes upon a conveyer so that they will automatically return to the kitchen.

Another object of the invention is to produce 50 a system whereby the trays used for carrying the food and empty dishes will travel to the desired places by the force of gravitation.

Another object of the invention is an effi-

cient arrangement of the kitchen so as to accommodate a system of this nature economically and so as to require the minimum amount of space.

Another object of the invention is the 60 production of simple and efficient means for changing the direction of the travel of the trays after they have reached the kitchen or are being sent from the kitchen to the dining-room.

Another object of the invention is the production of an electrically operated stop mechanism situated in front of each table so that the trays may be stopped in their travel without jarring the contents thereof. 70

Another object of the invention is the production of a card system whereby the order of the patron may be taken care of and the charges thereof correctly noted.

A still further object of the invention is 75 to generally improve upon devices of this character by providing a device which will be comparatively simple, extremely durable and inexpensive in construction, one which is both efficient and reliable in operation and 80 well adapted to the purpose for which it is designed.

With these and numerous other objects in view, the invention resides in certain novel features of construction and the combination and arrangement of parts as will be hereinafter fully described and claimed.

In the accompanying drawings:

Figure 1 is a top plan view showing the general arrangement of our system, 90

Fig. 2 is a fragmentary top plan view of one corner of the kitchen construction showing the walls and other parts thereof in section,

Fig. 3 is an end elevation of the central 95 conveyer looking from the front of the lunch room,

Fig. 4 is a side elevation of one of the centrally situated conveyers, parts thereof being broken away,

Fig. 5 is a fragmentary top plan view of the centrally located conveyers showing the end nearest the entrance of the lunch room,

Fig. 6 is a fragmentary side elevation of one of the side conveyers, showing parts 105 thereof broken away,

Fig. 7 is an end elevation of one of the side conveyers looking from the front of the lunch room,

Fig. 8 is a fragmentary side elevation of 110

one of the side conveyers, showing the same as it enters the kitchen and parts thereof broken away.

Fig. 9 is a fragmentary detail perspective view of the bracket which is used for supporting the conveyer run-ways,

Fig. 10 is a section taken through the kitchen looking out toward the dining-room showing the position occupied by the operator who controls the operation of the trays,

Fig. 11 is a fragmentary top plan view of a portion of one of the side conveyers and the table and seating capacity used in connection therewith,

Fig. 13 is an elevation showing the mechanism for changing the direction of the travel of the trays in the kitchen,

Fig. 14 discloses detailed views of the mechanism used in connection with the construction disclosed in Fig. 13 and the operation thereof,

Fig. 15 is a section taken through one end of the rollers used in connection with the construction shown in Fig. 13 showing the means used for mounting the same,

Fig. 16 is a top plan view of the mechanism shown in Fig. 13,

Fig. 17 discloses views of the spring used in connection with the mechanism disclosed in Fig. 16,

Fig. 18 is a side elevation of the stop used in connection with the trays,

Fig. 19 is an end elevation of the construction shown in Fig. 18,

Fig. 20 is a side elevation of the rollers used upon the conveyer run-ways,

Fig. 21 is a top plan view of the construction shown in Fig. 20,

Fig. 22 is a longitudinal sectional view showing the mechanism for stopping the trays,

Fig. 23 is an end elevation of the mechanism shown in Fig. 22 parts thereof being shown in section,

Fig. 24 is a top plan view of the mechanism shown in Fig. 22,

Fig. 25 is a side elevation of the complete stop mechanism showing the same in operation,

Fig. 26 is an elevational view of the bracket used for supporting the solenoid,

Fig. 27 is a detailed sectional view of the core of the solenoid,

Fig. 28 is a top plan view of the solenoid,

Fig. 29 is a bottom plan view of the tray,

Fig. 30 is a sectional view taken on the line 30—30 of Fig. 29,

Fig. 31 is a fragmentary view of the receiving clerk's order sheet,

Fig. 32 is a front view of the menu card,

Fig. 33 is a view of the customer's check.

Fig. 34 is a diagrammatical view of the electrical circuit used in connection with this system, and

Fig. 35 is a fragmentary perspective view of a slightly modified form of our system.

Referring to our system in detail it will be readily seen that R represents the lobby or reception room which may have any desirable entrance so that the customer or patron may enter. A bench 1 is provided

in the reception room and the patron will be given a bill of fare or menu card from

which he may select the desired articles by punching the card shown in Fig. 32 of the

drawing in the designated column opposite the article desired. This card will then be

given to an attendant positioned at 2 who will telephone the order to the kitchen to be filled and will assign a number to the customer and this number will be placed upon the card.

A check such as shown in Fig. 33 of the drawing will be presented to the customer upon which will appear his seat number and this check will also be punched so

as to designate the total cost of purchase.

In order to save time and afford accuracy in this system each article on the bill of fare will be given a number shown in the card illustrated in Fig. 32 and the operator at 2

will telephone these numbers, the first number designating the customer's seat number and this will be placed upon a sheet such as

is shown and illustrated in Fig. 31. The attendant in the kitchen may then check the remaining number upon his sheet and the order will then be filled in a manner to be

hereinafter described. In the meantime the customer has passed through the turnstile indicated at 3 in Fig. 1 and has taken the

seat in the lunch room corresponding to the number upon his check.

The general arrangement of the lunch room is disclosed in Fig. 1 and it will be seen that conveyers are arranged along the side walls as indicated by the letters A and

D and that there are also centrally located conveyers B and C. All the tables 4 ar-

anged alongside of the conveyers B and C are individual tables and are provided with the seats 5 whereas the tables 6 along the

walls and conveyers A and D are arranged so as to accommodate two persons, the seats

7 being preferably arranged opposite the ends of the tables 6. Coat hangers 8 may

be arranged in the aisles of the lunch room at suitable intervals.

By referring especially to Fig. 1 of the drawing it will be seen that the kitchen is arranged so that the top portion of the con-

veyers A and D will lead toward the rear thereof so that a dish washing machine may

be situated at the terminal thereof for re-

ceiving the dirty dishes. The dishes may

then be placed upon the table 10 for draining

and of course afterward removed wher-

70

75

80

85

95

100

105

110

115

120

125

130

ever may be desired. A range 11 is situated centrally and to the rear of the kitchen and we prefer to have the ice boxes 12 and the pantries 13 situated upon each side of this range, that is, there will be two pantries and two ice boxes so that one attendant may fill the conveyers A and C while another attendant will attend to the conveyers B and D. Of course, it will be readily understood that during those hours of the day when business is not very rushed it will be necessary and probably very desirable only to use one of the conveyers and of course during such hours only a portion of the kitchen need be used. At 14 we have shown a steam table upon which dishes which are greatly in demand may be placed so as to be readily accessible and quickly obtained for placing upon the trays. By referring to Figs. 3 and 4 of the drawing it will be seen that the central conveyers B and C are supported upon the pedestals 15 which may be of any preferred construction and as shown have the supporting braces 16 extending at right angles therefrom at the top thereof so as to support the tables 4. Standards 17 are vertically attached to the tables 4 so as to support the upper conveyer 18 and the lower conveyer 19. By referring especially to Fig. 4 of the drawing it will be seen that the upper conveyer 18 slants toward the kitchen at the left while the conveyer 19 slants toward the front of the lunch room at the right and thus it will be readily understood that the conveyer 19 delivers the food to the customer while the conveyer 18 returns the trays and dirty dishes to the kitchen. The numeral 20 designates condiments and sugar and milk containers or supports of any preferred construction which are situated between the individual tables 4. In Fig. 5 of the drawing it will be seen that the conveyer 18 is provided with spaced apart grooves for receiving the strips 25. The conveyer 19 is similarly constructed. A plurality of rollers 23 are suitably mounted on these strips 25. The construction of these rollers 23 is more clearly brought out in Figs. 20 and 21 of the drawing and it will be noted that they taper to a rather narrow periphery and are each provided with a spindle 24 which is journaled in the strip 25 in any preferred manner. In Figs. 6, 7, and 8 there is illustrated the construction of the side conveyers A and D. The conveyers A and D have a top conveyer 18 and a bottom conveyer 19 supported by the standards 17. This whole mechanism is carried upon the brackets 26 which are preferably situated adjacent the tables 6 so as to aid in the support thereof. Otherwise these conveyers 18 and 19 are similar to the construction already described for conveyers B and C. In Fig. 9 of the draw-

ing we have shown a detailed perspective view of the bracket used for supporting the conveyers 18 and 19. This bracket may be held in engagement with the standards 17 in any desired manner. 70

As stated above the tables 6 which are arranged along the conveyers A and D are provided with the seats 7 at each end thereof as is clearly brought out in Fig. 11 of the drawing and it will be noted that condiment supports or containers 27 extend out over those tables for the use of the patrons. It will also be noted in Fig. 11 that the patron may easily remove the tray from the lower conveyer 19 and after having finished his meal may easily place the same upon the upper conveyer 18. 75

By referring to Figs. 1 and 2 of the drawing it will be noted that the empty trays which will be placed upon the top conveyer 18 of the conveyer mechanisms C and B will travel toward the kitchen because of gravitation and after having passed through an opening provided in the wall 28 separating the kitchen from the dining room proper it will be necessary to change the direction of the travel of these trays so that they will travel sidewise along the conveyers 29 to the extension 30 of the conveyers A and D and then to the dish washing machine. It will also be noted that one of the conveyers 29 is provided with the hinged portion 32 so that the same may be raised so as to allow the attendants to pass from the front portion of the kitchen to the rear thereof. 100

In Figs. 10, 12, 13, 14, and 16 we have illustrated in detail this transferring mechanism. It consists of a hinged frame 33 having the transverse rollers 34 mounted therein. These rollers 34 are hollow in construction, and have cylinders at each end provided with a depression therein for receiving the end 36 of the supporting bracket 37 which is fixedly attached to the frame 33 in any desired manner so that these rollers will be operated upon a level higher than the frame 33 itself. The frame 33 is hinged at 38 and these hinges 38 may be of any preferred construction having a spring therein for returning this frame 33 in a horizontal position so as to be in alinement with the upper conveyer 18 of the conveyers B and C. Spring arms 39 which are shown in detail in Fig. 17 are disposed along the side portions of the upper conveying mechanisms B and C adjacent the frame 33 so that after the tray has passed on to this frame it cannot accidentally be moved back upon the conveyer 18. At the kitchen end of each of the frames 33 is a latch 40 which will be formed of spring metal and have portions 41 and 42 reinforced. At the terminal of the portion 42 a plunger 43 is situated so that the tray will abut it thus releasing the latch from engagement with the frame 33 so 130

as to allow the same to drop as indicated in Fig. 13 of the drawing, it, of course, being understood that the frame 33 normally rests upon the portion 41 of the latch 40. After 5 the frame 33 has dropped so as to be in alinement with the conveyer 29 the tray will slide from the rollers on to this conveyer 29 and travel toward the extension 30. A similar mechanism will be situated at the connection 10 between the conveyers 29 and 30 so as to deliver the tray to the extension 30 over which it will pass to the dish washing machine.

Upon the lower conveyer 19 there are provided 15 a plurality of elongated slots 43' which are situated opposite the various tables and so as to support a stop mechanism which will now be described. This stop mechanism consists of a tubing 44, within 20 which is situated the expansion coil spring 46. A slot 47 is provided in the upper portion of the tubing 44 and extends longitudinally therealong. A lug 48 having a cylindrical shank 49, situated within the tubing 25 44, abuts the tray for stopping the movement thereof. This lug having the shank 49 will act as a buffer since the spring 46 will absorb the shock and thus slowly retard the speed and finally stop the tray in its 30 travel. A web 50 is mounted upon the lower portion of the tubing 44 adjacent the free end thereof and is provided at its end with a knuckle through which passes a pivot pin 44' carried by the bracket 56. The link 51 is 35 integral with the knuckle and is provided with an elongated aperture at one end so as to receive the pin 52 which is held between the ears 53 situated on the top of the solenoid's core 54. The solenoid 55 is of conventional 40 construction and is situated upon the bracket 56 as is clearly shown in Figs. 25 and 26. When the solenoid is energized the core thereof will be forced downwardly thus raising the stop mechanism to an operative 45 position. The core of the solenoid 56 is made in two sections which are connected by means of a threaded stud 57 as is clearly shown in Fig. 27 for facilitating the assembling thereof.

50 In Figs. 18 and 19 we have shown a slightly modified form of this stop mechanism which is used at the ends of the conveyers 19 and consists of the tubing 44 having the lug 48 therein similar to that which has already been described. Brackets 59 depend from the tubing 44 and thus hold this mechanism in an operative position at all times.

The tray which we prefer to use in our 60 system is shown in detail in Figs. 29 and 30 and is substantially rectangular in shape and consists of a conventional body portion 60 having upwardly extending flanges. Tracks are situated along the bottom face of 65 the tray and are formed of the parallel ribs

61 which are slightly spaced apart so as to receive the roller 23 therebetween.

In Fig. 10 is illustrated a corner of the kitchen adjacent the terminal of the conveyer B showing the position of the despatch 70 table 45 close to which are situated a plurality of pilot lights 21 each pilot light corresponding to a seat number and a switch board 62 is also provided having a switch corresponding to each seat along the 75 conveyer B. A similar switch board and similar pilot lights are situated adjacent the terminals of each of the conveyers A, C and D.

Referring to Fig. 34 wherein is illustrated 80 a diagrammatical view of the wiring used in connection with this system it will be noted that the strips 25, are, of course, arranged in pairs and one of these strips is formed in sections and in this figure we 85 have designated each section as 25'. This sectional strip 25' is formed of metal so as to be an electrical conductor for the purpose to be later described. It should also be understood that the trays are also formed of 90 an electrical conducting material. The numeral 63 represents the source of current which passes through the wire 64 and branches into the wires 65 and 66'. It will only be necessary to trace one of the circuits 95 and we will now trace the circuit appearing to the left of Fig. 34 and the other circuits are exact duplicates thereof. The current passes from the battery or source of current 63 through the wire 64 and through the wire 100 65. The switch 66 being closed the current will pass through the wire 67 and actuate the solenoid 55 and then return through the wires 68 and 69 to the battery. It will be also noted that as the tray comes into contact with the strip 25' the corresponding 105 pilot light 21 will be lighted so that the operator may know exactly where the tray is at all times during its travel. As the tray contacts with the strip 25' a circuit will 110 be closed so that the current will pass from the battery 63, through the wire 64, through the wire 65, through the pilot light 21, through the wire 70, through the strip 25', through the tray, through the strip 25 and 115 returned through the wire 75 and wire 65 to the battery 63. Thus it will be seen that as soon as the tray has arrived at its destination the operator will be notified and as soon as the tray has been removed from the lower 120 conveyer the light will be extinguished since the circuit will have been broken and he will again be notified that this lower conveyer is clear for the next tray.

The above described system may be constructed of hard wood and decorated to suit the fancy of the owner and may also be illuminated with any lighting system desired. Of course, this system may be constructed of sheet steel pressed to the different shapes 130

and the various electric portions of the system may be insulated from the conveyer in a well known manner. It will also be seen that the usual number of kitchen employees 5 together with three extra helpers or despatchers will operate the entire system as described. Waiters will be eliminated from the dining room entirely and thus there will be no undue handling of food which will 10 insure additional sanitation and because of the efficiency will reduce the cost of operation and allow the proprietor to serve meals at a reduced rate.

The modification which has just been described is used in the ordinary transient lunch room wherein the customer orders his meal. In the slightly modified form shown in Fig. 35 of the drawing we have shown what we call the factory system wherein two 20 or three meals may be served at the same time. A bill of fare will be placed in front of each conveyer so that the customer may see the bill of fare which is served at this conveyer and will take a seat alongside 25 thereof. The despatcher seeing him seated will immediately despatch a tray to him with the designated meal thereon and a stop mechanism will be used in this system similar to that already described. It is not 30 thought necessary to again illustrate this in connection with this modification.

Referring to Fig. 35 it will be seen that the system comprises the elongated table 70' having the standards extending uprightly 35 therefrom as is indicated at 17'. A bottom conveyer 19' is constructed similar to the other modification for receiving the trays used in the other modification. A top conveyer 18' is mounted upon the tops of the 40 standards 17' and slant toward the kitchen while the conveyer 19' slants toward the front of the lunch room and thus gravitation will furnish power for moving the trays. In this modification we have located 45 a shelf 71 between the lower and upper conveyers 19' and 18' upon which may be placed salt and pepper and other seasoning material as may be desired.

From the foregoing description, taken in 50 connection with the accompanying drawings, the construction and operation of the system will be readily understood without a more extended explanation. As numerous changes in form, proportion, and in the 55 minor details of construction may be resorted to without departing from the spirit of these systems, we do not wish to be limited to the construction herein shown and described other than as claimed.

60 Having thus described our invention what we claim as new is:—

1. A system comprising a reception room, an eating room, a kitchen, a conveyer leading from the kitchen to the end of the eating 65 room and adjacent the reception room and

slanting downward from the kitchen, trays adapted to travel on said conveyer, and means disposed along the conveyer for stopping the trays at desired points therealong.

2. A system of the class described comprising a dining room, a kitchen, a conveyer leading from said kitchen to said dining room, a tray adapted to travel on said conveyer, electrically operated means for stopping said tray at a desired point on said 70 conveyer, a pilot light for designating the desired point on said conveyer, and means for illuminating said pilot light when said tray has arrived at said desired point.

3. A system of the class described comprising a dining room, a kitchen, a pair of centrally located conveyer mechanisms longitudinally arranged throughout the dining room and passing into the kitchen, a pair of conveyer means arranged along the sides 80 of the dining room and passing into the kitchen, said conveyer mechanisms comprising an upper and a lower conveyer, trays for traveling on said conveyers, said upper conveyer of the centrally located conveyer 85 mechanisms provided with means at their kitchen ends for delivering the empty trays to the side conveyer mechanisms.

4. A transferring conveying mechanism to be used with a system of the class described comprising a hinged frame, a conveyer leading into said hinged frame and a second conveyer leading therefrom, and means for normally holding said frame in alinement with the first mentioned conveyer. 95

5. In a device of the class described, the combination of two conveyers disposed at right angles to each other, a hinged frame disposed between said conveyers, one of said conveyers being disposed at a level 100 lower than the other conveyer, means for normally holding said frame in alinement with the higher conveyer, and means for automatically allowing said frame to drop in alinement with the lower conveyer. 110

6. In a device of the class described, the combination of two conveyers disposed at right angles to each other, a tray adapted to travel on said conveyers, and means for transferring said tray from one conveyer to 115 the other conveyer so that the same will travel in another direction.

7. In a device of the class described, the combination of two conveyers disposed at right angles to each other and one of said 120 conveyers being positioned at a higher level than the other, a hinged frame disposed between said conveyers, stop mechanisms positioned at the end of the higher conveyer, a tray for traveling on said conveyers, means 125 provided for holding said frame in alinement with the higher conveyer, and means actuated by the tray for allowing said tray to drop to a level with the lower conveyer.

8. In a device of the class described, a 130

conveyer comprising a central board, side boards disposed on each side of said central board and spaced therefrom, ribs disposed between said central board and said side boards, slots provided in said ribs, rollers situated in said slots for the purpose specified.

9. A tray to be used with a device of the class described comprising a body portion, 10 a pair of tracks disposed on the bottom face of said body portion, and each track comprising a pair of spaced apart ribs.

10. In a system of the class described, a menu card having a blank thereon for placing a seat number, a kitchen order sheet having a space thereon for putting the corresponding seat number, and an individual price check having a space thereon for the same seat number.

11. A stop mechanism to be used with a

device of the class described comprising a hollow tube, means provided for mounting the hollow tube in said device, a lug slidably mounted in said hollow tube, means for normally holding said lug at one end of said hollow tube and means for pivotally operating said tube in said device for the purpose specified. 25

12. A stop mechanism to be used with a device of the class described comprising resilient means for engaging a tray and electromagnetic means for moving said resilient means to an operative position. 30

In testimony whereof we affix our signatures in presence of two witnesses.

CHARLES H. SPINK.
VICTOR D. GARNS.

Witnesses:

JOHN WEIR,
JOHN F. WERTZ.
